UNITED STATES PATENT OFFICE.

GEORGE W. DOVER, OF PROVIDENCE, RHODE ISLAND.

CURTAIN HANGER.

Application filed December 3, 1925. Serial No. 72,895.

This invention relates to an improved curtain hanger adapted to carry a plurality of curtain draperies and hold the same in its normal position in front of the upper portion of the window, 55

One object of the invention is to provide a curtain hanger of the character described which extends across the front of the window and is provided with separate curtain supporting sections and one or more intermediate sections adapted to connect the curtain supporting sections in such manner as to provide an extensible structure for fitting windows of varying widths.

Another object of the invention is to provide a curtain hanger and means for holding the same whereby the hanger may be retained in its normal curtain supporting position across the upper portion of the window or moved bodily into lowered position and there supported where easy access may be had thereto to remove curtain draperies therefrom and replace them with others when desired.

A further object of the invention is to provide upper and lower brackets adjacent to the top of the window and at a suitable point below the top of the window which cooperate to support the curtain hanger across the window adjacent to the top thereof, or permit the utilization of the lower brackets to support the curtain hanger at a suitable point below the top of the window to permit the removal of draperies therefrom and their replacement by others when desired.

Another object of the invention is to provide a curtain hanger of the character described which may be employed without the aid of upper brackets, to support the curtain draperies across the upper portion of the window.

Another object of the invention is to provide supporting brackets which may be secured to the top or sides of the window casing, thereby avoiding the marring of the front portions of the window casing.

Other objects and advantages of the invention relate to various improved details of construction and improved methods of operation as will be more fully set forth in the detailed description to follow.

Referring to the drawings:

Fig. 1 is a front elevational view of one

form of the invention, illustrating the same in its normal position in front of the upper portion of the window,

Fig. 2 is a side elevational view of the structure shown in Fig. 1,

Fig. 3 is a top plan view of the structure shown in Fig. 1,

Fig. 4 is an enlarged perspective view of the lower bracket member shown in Fig. 1,

Fig. 5 is an enlarged perspective view of one of the vertical standards shown in Fig. 1,

Fig. 6 is a side elevational view of a modified form of the invention,

Fig. 7 is an enlarged detail sectional view of the clip, taken along the line 7—7 of Fig. 3,

Fig. 8 is a top plan view of the structure shown in Fig. 6,

Fig. 9 is an enlarged detail sectional view, taken along the line 9—9 of Fig. 3,

Fig. 10 is a perspective view of the lower bracket as shown in Fig. 6 of the drawings,

Fig. 11 is a side elevational view of a further modified form of the invention,

Fig. 12 is an enlarged sectional view taken along the line 12—12 of Fig. 11,

Fig. 13 is a perspective view of the lower bracket shown in Fig. 11,

Fig. 14 is an enlarged view of the lower nut shown in Fig. 11,

Fig. 15 is a front elevational view of the structure shown in Fig. 11,

Fig. 16 is a side view of the end portion of one of the extension members, and,

Fig. 17 is an enlarged detail sectional view showing the manner of mounting one of the central extension members on one of the curtain supporting sections.

In that form of the invention illustrated in Figs. 1, 2, 3, 4, 5 and 9, 1 designates the top, and 2 the sides of a window frame of the usual construction. The curtain hanger comprises vertical standards 3 of similar construction located upon opposite sides of

the frame and each provided with an upper curved portion 4 and terminating in a pointed end 5. Suitably located below the curved portion 4 is an offset 6 arranged to receive the inturned end portions 7, 8 and

9 of the curtain supporting sections 13, 14 and 15, and provided with an opening 10

whereby the curtain supporting sections may be secured to the standard by a bolt 11 and nut 12.

The curtain supporting sections of the hanger structures 13, 14 and 15 are bent to provide inturned ends 7, 8 and 9 respectively, these inturned ends being firmly secured together and held in the offset 6 of the standard 3 by the bolt 11. Those portions of the curtain supporting sections 13, 14 and 15 which project across the front of the window frame are spaced progressively from each other as shown in Fig. 3 of the drawings, and the oppositely positioned curtain supporting sections 13 and 15 have their adjacent end portions connected by extension members 16 and 17 respectively, said extension members 16 and 17 being so formed as to slip over the adjacent end portions of the curtain supporting sections 13 and 15 and slide thereon to connect the curtain supporting sections 13 and 15 on frames of varying widths and thus serve to support respectively the window curtains and the valance across the front of the window frame. The curtain supporting sections 14 are each provided with a relatively short extension member 18 which is formed to slide over the inwardly projecting end portion of each section 14 and is adjustable thereon for supporting the drop curtains 20 at each side of the window. The opposite curtain supporting sections 13 and extension member 16 serve to support the usual curtains; each curtain supporting section 14 and its extension member 18 supports a drop curtain upon one side of the window; and the curtain supporting sections 15 and extension member 17 support the valance across the front of the curtains. The opposite curtain supporting sections 13 and 15 and vertical standards 3 are normally held together and in assembled position by means of the extension members 16 and 17 so that the entire curtain supporting structure may be bodily moved as a unit.

Each drop curtain is preferably provided with a loop 22 formed at the upper edge which slides over the extension 18 and section 14, and each drop curtain may be retained in proper position upon its support by means of a spring clip 23 provided with outwardly projecting ends 24 which may be positioned within the extension member 18 when they engage the fabric of the loop and positively hold the curtain against slipping on its support.

Brackets 26 may be secured to the top portion of the window frame by screws or like fastening devices 27, each of said brackets being provided with an opening 28 for the reception of the end 5 of one of the standards 3. The lower end of each standard 3 is bent inwardly as at 29 to rest

against the frame whereby the main portion of the standard is maintained substantially parallel with the frame when the standards are in normal position as shown in Fig. 2. Lower brackets 30 are secured to opposite sides of the frame by screws or similar fastening means 31, each of said brackets having an outwardly extending portion 32 over which the end 5 of the standard is hooked when the hanger is placed in its lowered position to support the same for the removal or replacement of the curtains.

When the hanger is in its normal curtain supporting position, as shown in Fig. 1 of the drawings, the pointed ends 5 of the standards 3 may be placed within the openings 28 in the brackets 26 and the lower portion of each standard positioned beneath the outwardly extending portion 32 of the lower bracket 30, whereby the curtains are supported in front of the window in such a manner that the entire supporting structure and curtains may be bodily removed from the window if desired and without removing the curtains from the hanger. When it is desired to remove or replace the curtains carried by the hanger the entire structure is removed from the position shown in Fig. 1 by grasping the standards 3 and lifting the pointed ends 5 from the openings 28 in the brackets 26. The structure is then lowered and the pointed ends 5 hooked over the outwardly extending portions 32 of the lower brackets which serve to support the structure in position for the removal and replacement of the curtains on the curtain supporting sections. This structure may also be employed without using the top brackets 26 by engaging the pointed ends 5 with the top of window frame when the pointed ends 5 may be forced into the wood of the frame sufficiently to prevent the removal of the structure except when it may be desired to change or remove the curtains.

In the forms of the invention illustrated in Figs. 6, 8 and 10 to 15 inclusive of the drawings, the vertical standards 35 upon opposite sides of the frame are of similar construction and are in the form of shafts each provided with a threaded upper end 36 and having a reduced portion 37 located adjacent to the upper end thereof. In the modification shown in Figs. 6, 8 and 10 of the drawings, the shafts 35 are each provided with a nut 38 mounted on the threaded portion 36 for carrying the curtain supporting sections 39, 40 and 41. Each of these curtain supporting sections 39, 40 and 41 is provided with a hub portion 43 shaped to fit over the threaded portion 36 of the shafts 35 where they are held secured by nuts 42. The curtain supporting sections 39, 40 and 41 being so formed that they project from

the hub portions at different points circumferentially of the shaft 35 and are spaced from each other horizontally, as shown in Fig. 8 of the drawings.

Extension members 45 and 46, similar to the extension members 16 and 17, connect the adjacent ends of the curtain supporting sections 39 and 41 respectively, and are slideable thereon to provide extension means for supporting the curtains and valance respectively and for adapting these curtain supporting sections to fit windows of varying widths. The curtain supporting sections 40 are each provided with an extension member 48 slideable thereon and adapted to slide upon said sections to vary the effective lengths of said curtain supports as may be desired. Clips 23, similar to those previously described and similarly employed, may be used for the purpose of securing the edges of the drop curtain in proper position relative to the ends of the extension members 48. The opposite curtain supporting sections 39 and extension member 45 serve to support the usual curtains; each curtain supporting section 40 and its extension member 48 supports a drop curtain upon one side of the window; and the curtain supporting sections 41 and extension member 46 support the valance across the front of the curtains. The opposite curtain supporting sections 39 and 41 and vertical shafts 35 are normally held together and in assembled position by means of the extension members 45 and 46 so that the entire curtain supporting structure may be bodily moved as a unit. In the form of the invention shown in Figs. 6 and 8 of the drawings the curtain hanger structure is supported by top brackets 50 secured to the top of the window frame by screws or other suitable fastening means 51, and by lower brackets 52 secured to the frame by screws or other suitable fastening means 53. Each of these brackets is provided with a bearing opening 54 having a narrowed slot 55 communicating therewith, the narrowed slot 55 being adapted to receive the reduced portion 37 of the shaft 35, while the opening 54 is of suitable size to form a bearing for the main portion of the shaft 35.

When the curtain draperies have been placed in position on the curtain supporting members the hanger structure is placed in the position shown in full lines in Fig. 6 by first inserting the lower ends of the shaft 35 in the bearing openings of the lower brackets 52 when the reduced portions 37 of the shafts are then passed into the narrowed slots 55 of the upper brackets and the structure is lowered into position shown in full lines in Fig. 6 of the drawings, where the structure is supported in front of the window and positively held against removal until the structure is raised to bring the re-

duced portions 37 into registry with the narrowed slots 55. Whenever it is desired to remove or change the curtains, the supporting structure is raised until the reduced portions 37 register with the narrowed slots 55 when the shafts are removed from both the upper and lower brackets and the structure lowered to a point adjacent to the lower brackets 52. The reduced portions 37 of the shaft are then passed into the narrowed slots 55 of the lower brackets and lowered into position to be supported thereby as shown in dotted lines in Fig. 6 of the drawings, when the curtains may be readily removed and replaced. In this way the entire curtain supporting structure may be bodily removed from its normal position in front of the window and lowered to a position within easy reach to remove or replace the curtains, and then returned to its original position, without making it necessary for the operator to reach the upper portion of the window frame.

In that form of the invention particularly illustrated in Figs. 11, 13, 14 and 15 of the drawings, the structure is in all respects similar to that just described except that the lower nut 55 supporting the hub portions 43 of the curtain supporting sections on the shaft 35 is provided upon its lower side with a reduced shoulder 56, and the top bracket 57 and lower bracket 58 for securing the structure to the frame are each provided with a slot 59 of sufficient size to receive the shaft 35 and the outer edge of each bracket is turned up to form a flange 60 adapted to engage the reduced portion 56 of the nut 55 when the shaft 35 is placed in the slot 59 and the structure lowered into either the full line or dotted line position shown in Fig. 11 of the drawings. The bracket 57 is secured to the top of the frame by means of a screw 61 or similar fastening device, and the bracket 58 is secured to the side of the frame by a screw 62 or similar fastener.

The curtain draperies are applied to the structure shown in Figs. 11 and 14 in the same manner as previously described, and the structure can be readily placed in its normal position at the top of the window as shown in full lines on Fig. 11 where it is held in position by the shoulder 56 engaging the flange 60 of the top bracket 57. When it is desired to remove or change the curtains the structure may be removed from its full line position in Fig. 11 by disengaging the shafts 35 from the upper brackets and lowering them to the dotted line position shown in Fig. 11 where the shafts 35 are placed in the slots 59 of the lower brackets 58 so that the shoulders 56 of the nuts 55 engage the flanges 60 of the lower brackets to support the structure during the removal and replacement of the curtains.

The inner ends of the extensions 18 and 48 may be struck down as indicated at 63 in Fig. 16 of the drawings to prevent the clip 23 from sliding out of the end of the extension member when in position to hold the edge of the drop curtain in place.

What I claim is:

1. A curtain hanger comprising oppositely positioned vertical standards each of which supports a plurality of end sections, extension members connecting certain of said oppositely positioned end sections, standards supporting the end sections, and means engageable by said standards to support said hanger in either of two vertical positions in front of a window.

2. A curtain hanger comprising oppositely positioned vertical standards, curtain supporting sections carried by each standard and spaced from each other horizontally, an extension member slidably mounted upon and connecting two oppositely positioned correspondingly located curtain supporting sections to provide a continuous curtain support extending between the oppositely positioned standards, and means engageable by said standards to support said hanger in front of a window.

3. A curtain hanger comprising oppositely positioned vertical standards, curtain supporting sections carried by each standard and spaced from each other horizontally, an extension member slidably mounted upon and connecting two oppositely positioned correspondingly located curtain supporting sections to provide a continuous curtain support extending between the oppositely positioned standards.

4. A curtain hanger comprising oppositely positioned vertical standards, curtain supporting sections carried by each standard and spaced from each other horizontally, extension members, slidably mounted upon and connecting certain of the oppositely positioned correspondingly located curtain supporting sections to provide continuous curtain supports extending between the oppositely positioned standards, and means engageable by said standards to support said hanger in front of a window.

5. A curtain hanger comprising oppositely positioned vertical standards, curtain supporting sections carried by each standard and spaced from each other horizontally, extension members slidably mounted upon and connecting certain of the oppositely positioned correspondingly located curtain supporting sections to provide continuous supports extending between the oppositely positioned standards.

6. A curtain hanger comprising oppositely positioned vertical standards, curtain supporting sections carried by each standard and spaced from each other horizontally, an extension member slidably mounted upon

and connecting two oppositely positioned correspondingly located curtain supporting sections to provide a continuous curtain support extending between the oppositely positioned standards, and means engageable by 70 said standards to support said hanger in either of two vertical positions in front of a window.

7. A curtain hanger comprising two oppositely positioned vertical standards, a plurality of curtain supporting sections mounted upon each standard, an extension member slidably mounted upon and connecting said oppositely positioned sections to provide with said sections a continuous support, and 80 means for releasably supporting said sections upon opposite sides of a window.

8. A curtain hanger comprising oppositely positioned vertical standards, a plurality of curtain supporting sections mounted upon each standard and supported thereby, extension members slidably mounted upon and connecting certain correspondingly located oppositely positioned sections to provide with said sections continuous curtain supports, and means for releasably supporting said sections upon opposite sides of a window.

9. A curtain hanger comprising oppositely positioned vertical standards, a plurality of curtain supporting sections mounted upon each standard and supported thereby and an extension member slidably mounted upon and connecting two correspondingly located oppositely positioned sections to provide with said sections a continuous curtain support and unite the oppositely positioned standards and sections to form a substantially unitary structure.

10. A curtain hanger comprising oppositely positioned vertical standards, a plurality of curtain supporting sections mounted upon each standard and supported thereby and extension members slidably mounted upon and connecting certain correspondingly located oppositely positioned curtain supporting sections to provide with said sections continuous curtain supports and unite the oppositely positioned standards and sections to form a substantially unitary structure.

11. A curtain hanger comprising oppositely positioned brackets, oppositely positioned standards carried by said brackets, oppositely positioned curtain supporting sections carried by said standards, and members releasably connecting certain correspondingly located oppositely positioned curtain supporting sections to provide with said sections continuous supports and releasably connecting the oppositely positioned sections and standards to form in effect a unitary structure.

12. A curtain hanger comprising oppositely positioned upper and lower bracket mem-

bers, oppositely positioned standards, interconnected curtain supporting members carried by said standards, and means for supporting said standards from said upper and 5 lower bracket members in either of two vertical positions.

13. A curtain hanger comprising oppositely positioned upper and lower bracket members provided with recesses, oppositely positioned standards having portions adapted to engage the recesses in said brackets, interconnected curtain supporting members carried by said standards whereby said standards and curtain supporting members are 10 connected together to form a structure engageable with or removable from said brackets as a unit.

14. A curtain hanger comprising oppositely positioned standards each having its upper end portion downturned and terminating in a point, and oppositely positioned curtain supporting members carried by said standards.

15. A curtain hanger comprising oppositely positioned standards each having its upper end portion downturned and terminating in a point, and having an offset formed therein for the reception of curtain supporting members, and oppositely positioned curtain supporting members secured in the offset portions of said standards.

16. In a curtain hanger, a standard having its upper end portion bent back upon itself and terminating in a point, said

standard being provided intermediate its ends with an offset portion and having its opposite end inturned in the same direction as the bent upper end portion thereof.

17. In a curtain hanger, a curtain supporting section, an extension member slidably mounted upon said curtain supporting section and provided with inturned edges, and a spring clip provided with outturned edges adapted to fit within and engage the inturned edges of said extension member to 40 engage material interposed therebetween and maintain said fabric material in position relative to said extension member.

18. A curtain hanger comprising oppositely positioned vertical standards, a plurality 50 of curtain supporting sections carried by each standard, means slidably mounted upon and connecting certain of said oppositely positioned curtain supporting sections to form therewith continuous curtain supports extending across in front of the window and 55 connect the oppositely positioned standards and thereby form in effect a unitary structure bodily removable from and replaceable in position in front of the window, and upper and lower bracket members engageable by said standards to support said hanger in either of two vertical positions in front of a window.

In testimony whereof I have affixed my 65 signature.

GEORGE W. DOVER.
